UNITED STATES PATENT OFFICE.

JAMES HIRST, OF VINELAND, NEW JERSEY.

JAR OR BOTTLE CLOSURE.

SPECIFICATION forming part of Letters Patent No. 742,652, dated October 27, 1903.

Application filed May 18, 1903. Serial No. 157,640. (No model.)

To all whom it may concern:

Be it known that I, JAMES HIRST, a citizen of the United States, residing at Vineland, Cumberland county, New Jersey, have invented 5 certain Improvements in Jar or Bottle Closures, of which the following is a specification.

My invention relates to jar or bottle stoppers; and it consists of an improved form of paper disk stopper or sealing-cap of the character usually employed in connection with 10 milk-bottles for the purpose of making a temporary air and liquid tight closure.

My invention is fully shown in the accompanying drawings, in which—

15 Figure 1 is a sectional view of the improved sealing-cap forming the subject of my invention shown as applied to a bottle. Fig. 2 is a perspective view of the cap shown in Fig. 1; and Figs. 3, 4, 5, and 6 are views illustrating modified structures embodying my invention, Fig. 3 being a sectional view of Fig. 6, taken on the line *x x*.

In their simplest form the sealing caps or disks employed with milk-bottles consist simply of paper or pasteboard members cut approximately to the size of a shouldered recess in the inner wall of the bottle-neck. These caps or disks are pressed into place by suitable means and engage the inner wall of the 25 recess when in use. In this position the caps make quite a tight fit, and it is usually a difficult matter to remove the same. Numerous means have been suggested and provided for 30 accomplishing this result. Such means usually comprised the combination with the stopper of an extra element designed to serve as a projection or handle to be grasped by the thumb and finger, whereby the cap might be removed in a comparatively easy manner.

40 Such seals or stopper, however, having the additional element noted are more expensive than their value warrants. Hence the use of the ordinary plain flat disk has not been superseded to any great extent. My invention 45 provides means for removing the cap integral with such cap, which means do not add to the expense of the same and consist in forming a projection within and from the material of which the cap is composed, which 50 projection may be grasped by the thumb and finger to accomplish the removal of the cap.

In the preferred form of structure embody-

ing my invention, as illustrated in Figs. 1 and 2, 1 represents the main or flat portion of the disk, fitting the shouldered recess 2 of 55 the bottle 3. Extending above the main flat portion of the cap is a projection 4, preferably disposed in the center of the cap and which may or may not have a contracted neck portion. By grasping this projection with 60 the thumb and finger the disk or cap 1 is contracted toward the center, causing the edges opposite the thumb and finger to leave the shouldered recess, and the cap is thereby rendered readily removable. At the same time 65 the initial compression of the walls of the projection 4 will effect more or less compression of the air between the surface of the liquid in the bottle and the under surface of the cap, and such compression of the air will 70 tend to lift the cap at the center and assist in the removal of the same.

In the modification shown in Figs. 3 and 6 the projection 4^a comprises walls of the material which have been brought together or 75 compressed, as shown, and this form provides simply an engaging means for the thumb and finger and affords no compressing effect upon the air within the bottle.

In Fig. 4 I have shown a form of cap or 80 disk in which a bulbous projection 4^b is provided with a contracted neck portion 5.

In Fig. 5 I have shown a form of disk in which the projection 4^c is made by simply bunching up the central portion of the mate- 85 rial of which the cap or disk is composed.

Having thus described my invention, I claim and desire to secure by Letters Patent—

1. As a new article of manufacture, a jar 90 or bottle closure comprising a sealing-disk having an integral projection struck up from the material of which the disk is composed, said projection being discontinued some distance from the edges of said disk. 95

2. As a new article of manufacture, a jar or bottle closure comprising a sealing-disk having an integral projection struck up from the material of which the disk is composed, and confined to the central portion of the disk. 100

3. As a new article of manufacture, a jar or bottle closure comprising a sealing-disk having a bulbous projection struck up from the material of which the disk is composed.

4. As a new article of manufacture, a jar or bottle closure comprising a sealing-disk having a flat portion of circular shape adapted to fit within a recess in the neck of a bottle and having an integral, struck up, bulbous member projecting from the upper surface of the same.

5. As a new article of manufacture, a jar or bottle closure composed of an integral member of pasteboard or paper of circular shape adapted to fit within the recess of a bottle-

neck and having an integral hollow bulbous projection struck up from the surface of the disk, said projection serving as a handle for the finger and thumb in removing said disk. 15

In testimony whereof I have signed my name to this specification in the presence of two subscribing witnesses.

JAMES HIRST.
